DESIGN FOR A WASHING MACHINE AGITATOR

James B. Kirby, West Richfield, Ohio, assignor to
The Apex Electrical Manufacturing Company, Cleveland, Ohio, a corporation of Ohio, as trustee

Application November 15, 1937, Serial No. 72,860

Term of patent 14 years

To all whom it may concern:

Be it known that I, James B. Kirby, a citizen of the United States of America and a resident of West Richfield, in the county of Summit and State of Ohio, have invented a new, original, and ornamental Design for a Washing Machine Agitator, of which the following is a specification, reference being had to the accompanying drawing, forming part thereof.

In the drawing, Figure 1 is a front elevational view of a washing machine agitator, illustrating the design; Figure 2 is a top plan view of the agitator shown in Figure 1; Figure 3 is a view showing the cross-sectional outline of the blades on line 3—3, Figure 1; Figure 4 is a sectional view taken on line 4—4, Figure 1, with portions of the agitator omitted for the sake of clearness in illustrating the cross-sectional outline of the illustrated portion of the blades; and Figure 5 is a fragmentary sectional view taken on line 5—5, Figure 2, of the base and lower portion of the center-post of the agitator, the blades of the agitator being omitted from this view for the sake of clearness in illustrating the details of the agitator base.

I claim:

The ornamental design for a washing machine agitator, as shown and described.

JAMES B. KIRBY.
